UNITED STATES PATENT OFFICE.

HARRY J. SEVEL, OF GLENDALE, PENNSYLVANIA.

METHOD OF AND APPARATUS FOR FORMING SELF-LUBRICATING BEARINGS.

1,200,245.

Specification of Letters Patent.

Patented Oct. 3, 1916.

Application filed February 29, 1916. Serial No. 81,148.

To all whom it may concern:

Be it known that I, HARRY J. SEVEL, a citizen of the United States of America, residing at 237 Carothers avenue, Glendale, in the county of Allegheny and State of Pennsylvania, have invented certain new and useful Improvements in Methods of and Apparatus for Forming Self-Lubricating Bearings, of which the following is a specification.

This invention relates to a method of and apparatus for forming self-lubricating bearings.

It has heretofore been proposed to form bearings of Babbitt or other metals and to incorporate therein, inserts of graphite or other lubricating material to thereby render the bearing self-lubricating.

The present invention relates more particularly to an improved method and apparatus for forming bearings of this nature.

Further objects and advantages of the invention will be set forth in the detailed description which now follows:

In the accompanying drawings: Figure 1 is a side view of a bearing at one end of the connecting rod with the end of the connecting rod partly broken away; Fig. 2 is a perspective view of a half-bearing adapted for use in many locations; Fig. 3 is a plan view of the mold and the core with the several parts in assembled position; Fig. 4 is a vertical sectional view through the structure shown in Fig. 3; Fig. 5 is a detail perspective view of the core; Fig. 6 is a side view, and Fig. 7 is a plan view of the base of the mold; Fig. 8 is a perspective view of one of the graphite inserts; Fig. 9 is a view similar to Fig. 3 but showing the manner in which a half-bearing is formed.

Like numerals designate corresponding parts in all of the figures of the drawing.

The apparatus employed in forming a bearing in accordance with my improved method consists of a core 5 and a mold which comprises a base 6 and separable halves 7 and 8. The core 5 may taper slightly toward its upper end and it is provided with any desirable number of longitudinally extending dove-tailed recesses 9. These recesses receive the dove-tailed ribs 10 of lubricating inserts 11 preferably formed in blocks shaped as shown in Fig. 8. These inserts comprise dove-tailed body portions 12 which, when the core 5 is placed in the position illustrated in Fig. 4, project into the space be-

tween the outer face of the core and the inner face of the mold sections 7 and 8. It is to be noted that the base 6 is provided with a central opening 13 to receive the tapered end 14 of the core 5. The base is also provided with an up-standing boss 15 which is embraced by the mold sections 7 and 8 and by which the mold sections are held in centered and spaced relation to the core 5. The mold sections are clamped together by any suitable fastening devices such as nuts and bolts indicated at 16. The material such as Babbitt metal in a molten state is poured into the space between the outer face of the core and the inner face of the mold sections and closely engages the dove-tailed body portions 12 of the inserts 11. The Babbitt-metal is indicated at 17 in Figs. 1 and 4. There are two principal forms of bearings in use. One of these forms is illustrated in Fig. 1, and in this form the Babbitt metal 17 containing the inserts 11 is clamped between the halves 18 and 19 of the bearing end of a connecting rod and these halves 18 and 19 have flanges, one of which is indicated at 20, which overlap the ends of the Babbitt metal 17. Therefore in this form of bearing the inserts 11 may be formed to extend to the end of the Babbitt metal. Another form of bearing commonly employed is that illustrated in Fig. 2 wherein the Babbitt metal 17^a is itself provided with flanges 17^b and in making a bearing of this type I preferably make the blocks shown in Fig. 8 of such length that the inserts 11 terminate short of the ends of the Babbitt metal. After the bearing has been cast the mold sections 7 and 8 are removed and the core 5 is withdrawn from the bearing. This leaves the ribs 10 projecting into the bore that is to receive the shaft and to remove these ribs I pass a drill of the proper size through said bore to cut away these ribs and bring the surfaces of the inserts flush with the bearing surface 100 of the Babbitt metal, as illustrated in Figs. 1 and 2.

It is to be understood that the number of inserts and their size with relation to the diameter of the bearing may be varied at will, because in the case of heavy duty, slowly moving engines, it is desirable to have more bearing surface of Babbitt metal and fewer inserts than in the case of high speed engines where the load is comparatively light. In the latter case less bearing surface and more lubricating surface is de-

sired. Fig. 9 shows a construction adapted to form a half bearing. In this case only one of the mold sections, here designated as 7^a, is employed, together with a semi-circular core 5^a. The open side of the mold section is closed by a plate 5^b, otherwise the operation is the same as that hereinbefore set forth.

I extend the ribs 10 of inserts 11 beyond the body portions 12 of the inserts, as in Fig. 8, when forming bearings like those shown in Fig. 2, for the purpose of preventing the Babbitt metal from entering and filling the grooves of the core.

It is to be understood that the invention is not limited to the precise construction set forth but that it includes within its purview such changes as fairly come within the scope of the appended claims, because as far as I know I am the first to employ a core provided with means for detachably supporting lubricating inserts of this nature.

Having described my invention, what I claim is:

1. The herein described method of casting a bearing with lubricating inserts which consists of supporting the lubricating in-

serts slidably upon a core within a mold, casting the metal of the bearing about said inserts, withdrawing the core and leaving the parts of the inserts which were engaged with said core projecting into the bore of the bearing and then cutting said projecting parts off flush with the bearing face of the bearing.

2. An apparatus for forming bearings with lubricating inserts which consists of mold parts, a core and means for supporting said core centrally within said mold parts, said core having longitudinally extending grooves formed in its outer face and which grooves extend to one end of said core.

3. An apparatus for forming bearings with lubricating inserts which consists of mold parts, a core and means for supporting said core centrally within said mold parts, said core having longitudinally extending dove-tailed grooves formed in its outer face and which dove-tailed grooves extend to one end of said core.

In testimony whereof I affix my signature in presence of two witnesses.

HARRY J. SEVEL.
